UNITED STATES PATENT OFFICE.

GUSTAV GOERK, OF NEWARK, AND JACOB GOERK, OF IRVINGTON, NEW JERSEY.

SASH-FASTENER.

SPECIFICATION forming part of Letters Patent No. 739,410, dated September 22, 1903.

Application filed March 15, 1902. Serial No. 98,366. (No model.)

To all whom it may concern:

Be it known that we, GUSTAV GOERK, residing at Newark, and JACOB GOERK, residing at Irvington, in the county of Essex, State 5 of New Jersey, citizens of the United States, have invented certain new and useful Improvements in Sash-Fasteners; and we do hereby declare the following to be a full, clear, and exact description of the invention, such as 10 will enable others skilled in the art to which it appertains to make and use the same, reference being had to the accompanying drawings, and to letters of reference marked thereon, which form part of this specification.

15 The objects of this invention are to enable a sash to be locked automatically when the window is closed, to enable the locking to be effected with greater security against outside manipulation, to provide a device that is compact and neat in appearance and of small cost of construction, and to secure other advantages and results, some of which may be referred to hereinafter in connection with the description of the working parts.

25 The invention consists in the improved sash-fastener and locking device and in the arrangements and combinations of parts of the same, all substantially as will be hereinafter set forth and finally embraced in the clauses 30 of the claim.

Referring to the accompanying drawings, in which like letters of reference indicate corresponding parts in each of the several figures, Figure 1 is a perspective view of the 35 fastener applied to the portion of a window-sash, the same being shown in locked position. Fig. 2 is a view showing the parts when the window is open. Fig. 3 is a sectional detail of the upper sash member. Fig. 4 is a 40 sectional detail showing the lower sash member. Fig. 5 is a rear or inside elevation of the upper sash member, and Fig. 6 is an inside elevation of the lower sash member.

In said drawings, *a* indicates the upper 45 sash; *b*, the lower sash; *c*, the upper sash member of the fastener, and *d* the lower sash member of the said fastener.

The upper sash member *c* comprises a plate 50 *e*, adapted to be screwed down or otherwise fastened upon the upper rail of the sash *a*, and having integral with said plate *e* two ears

f, between which is pivoted on the pivot *g* a locking-lever *h*, of peculiar construction, the said pivot *g* being provided with a coil-spring *i*, bearing at one extremity upon the lever *h* and at the other extremity upon the frame or plate *e* or one of the ears thereof. The said lever *h* is provided at one end with a finger-piece *j*, which projects away from the pivot and ears *f* a distance sufficient to enable it to overlie the member *d*, so that when the said lever is fixed upon its pivot, as hereinafter described, the said sash member *d* and the sash thereof cannot be raised. The spring *i* tends to throw the said projecting 60 finger-piece over said member *d* when the said lever is released, as hereinafter described. The said lever *h* on its under side is provided with pivotal ears *h'* *h''*, between which the said spring *i* is arranged. One of said ears 70 is extended to form a locking-catch *k*, and the other of said ears is extended to provide a throwing-arm *l*. The latter when the finger piece of the lever is raised or turned toward the position shown in Fig. 3 projects 75 out to engage the bearing *o* of the catch member *d*, for a purpose hereinafter described. When the sash is drawn down, the said member *d* engages at the bearing *o* a locking-lever *m* to release the same from the 80 lip or catch *k*, so that the spring *i* may operate to throw the lever *j* to its locked position over the member *d*. The locking-lever *m* is pivoted upon a pin *n*, attached to one of the ears of the plate *e*, and projects forward into 85 the path of the bearing *o*, so as to be pressed down when the lower sash *b* is closed. The said lever *m* is provided on its upper side with one or more teeth or catching-bearings *k'* to engage the lip or catch *k*, and when the said 90 lever *m* is pressed down, as described, the lip or catch *k* will be disengaged from the tooth *k'*, as will be obvious upon examination of Fig. 3. The said lever *m* is furnished with a coil-spring *p*, which is arranged on the ful-

95 crum-pin *n* and has its ends engaged to the plate *e* and lever *m*, bearing upon the said lever *m*, so as to throw it automatically upward into its catching relation to the said lip *k*.

The parts being in the open relation shown in Figs. 2 and 3, upon closing down the lower

sash the bearing o' first engages the projecting lever m and releases the same from the locking-lever h , and the latter turns under the power of the spring i , so that the upward projection o' of the member d enters the recess h^3 of the lever to prevent the lower sash from being raised. Manipulation of the lever h from the outside by means of inserting a knife or the like between the sashes is obstructed by the lever m , projecting across the plane of meeting of the two members c d , and is further prevented by locating said plane of meeting of the members a little to one side of the plane of meeting of the sashes. To open the lower sash, the locking-lever h is raised by its finger-piece j up from the member d and automatically held in its raised position by the teeth of the catching-lever m , engaging the lip k on the rear end of the locking-lever. Obviously before the catching-lever m can raise to engage said lip k the sash member d of the fastener must have been lifted sufficiently to disengage its bearings o therefrom, and to effect this the throw-arm l of the locking-lever engages the bearing o' of the lower sash member b as the locking-lever is swung open and forcibly raises the lower sash member d a little, so that the catch m is free to act as described. It is sometimes desirable, as in washing the windows or the like, to hold the locking-lever h permanently inoperative, and to this end we have provided the catch member c on the outside of one of the ears f thereof with a normally open spring q , either flat, coiled, or otherwise, having at its free end a pintle r , which enters a perforation in the said ear and engages the lever j at a point eccentric to the shaft g to prevent turning. When it is desired to hold the lever in its position as shown in Fig. 3, it becomes only necessary to turn the lever h to its open position and press the spring q and pintle r , so that the latter enters into engagement with the back of the throwing-arm l to hold the lever in open position, the pressure of said arm against the pintle causing friction enough to overcome the tendency of the spring q to throw said pintle outward. Obviously under these conditions the sashes may be run up or down with the utmost freedom and with no danger of locking them, although the lower sash cannot be closed entirely down to the sill because of the engagement of the shoulder o' of its member with the lug k of the locking-lever. The crack thus left open, however, is not more than an eighth or a quarter of an inch and is immaterial under the circumstances when it exists. The catch-lever m is preferably provided with a series of ratchet-teeth k k' k'' to insure an automatic catching should one of the teeth

fail to perform its duties or to secure a certain catch under different adjustments of parts. The catch or fastener thus described is particularly desirable in connection with windows having meeting-rails that are not conveniently accessible, and in this event the lever j may be provided with a cord or other connection arranged over a pulley and adapted to be easily grasped by the hand and pulled to open position.

We are aware that various modifications may be made without departing from the spirit and scope of this invention, and consequently we do not wish to be limited by the positive descriptive terms employed, excepting as the state of the art may require.

Having thus described the invention, what we claim as new is—

1. In a sash-fastener, an upper sash member having a locking-lever provided with a catching-lip, a catching-lever adjacent to said locking-lever and adapted to engage the said lip thereof to hold the locking-lever in unlocked position, a spring normally holding said catching-lever in such engagement with the lip of the locking-lever, a lower sash member adapted to engage said catching-lever and release the same as the sashes are closed, and auxiliary means for holding the locking-lever inoperative independent of the said lever and catching-lever and lower sash member.

2. In a sash-fastener, the combination of two co-operating members, a locking-lever having at its rear extremity a catching-lip, a catching-lever pivoted beneath said locking-lever to engage said lip and projecting at its forward end to be engaged and released by the other sash member, and a throwing-arm upon said locking-lever adapted to raise the lower sash as the locking-lever is turned into idle position.

3. In a sash-lock, the combination with a sash member presenting upwardly-projecting parallel ears, a locking-lever pivoted between said ears and having at its rear end a catching-lip and a throwing-arm, of a catching-lever adapted to engage said lip, a co-operating sash member having bearing-surfaces for the said catching-lever and throwing-arm, and a slidable pin working through that ear adjacent to the throwing-arm and adapted to engage the rear edge of the latter as a stop.

In testimony that we claim the foregoing we have hereunto set our hands this 28th day of February, 1902.

GUSTAV GOERK.
JACOB GOERK.
